UNITED STATES PATENT OFFICE.

LEOPOLD GUTMAN, OF NEW YORK, N. Y.

SANITARY-SHAVING-OUTFIT PACKAGE.

1,188,443.

Specification of Letters Patent. Patented June 27, 1916.

Application filed July 2, 1915. Serial No. 37,662.

To all whom it may concern:

Be it known that I, LEOPOLD GUTMAN, a subject of the Emperor of Austria-Hungary, residing at 573 Second avenue, city, county, and State of New York, have invented new and useful Improvements in Sanitary-Shaving-Outfit Packages, of which the following is a specification.

This invention has for its object to dispense with the use of the manifestly unsanitary general shaving cups and brushes which are found in barber shops, and consists in the provision of individual shaving outfit packages to be vended by coin-controlled machines stationed in such places, convenient for use by the public. The shaving materials contained in these packages will be properly sterilized and sealed in impervious wrappers in the manufacture of the packages, so that their sanitary condition will be insured at the time of purchase. The construction of these shaving materials in practice is to be such that they will be capable of being used only once, whereby danger of further use by persons other than the first user will be prevented, and incidentally, the cost of the article will be reduced to a minimum.

To these ends the invention consists in the combination and construction of parts hereinafter, more particularly set forth and claimed, and illustrated in the accompanying drawing, in which:

Figure 1 is a side elevation of the completed brush, showing the casing of the package engaged with the brush head to serve as a handle therefor; Fig. 2 is a longitudinal sectional view through the package when ready for vending purposes, the shaving materials being collapsed and sealed therein; Fig. 3 is a perspective view of the collapsible cup, showing the same folded and ready to roll; Fig. 4 is a similar view of the cup when expanded and mounted in a permanent holder; and, Fig. 5 is a longitudinal sectional view of the brush head alone.

Referring to the drawings by numerals, and particularly to Fig. 2, 1 designates the outer casing which is constructed preferably of cardboard, though it is to be understood that it may be constructed of metal or any other material which is found in practice to be most suitable. It is shown in the present drawings also as being substantially cylindrical in form, but it may

have any other convenient cross-sectional contour. Within this casing the shaving materials, consisting in this instance of the cup 2 and the brush head 3, are fitted, they being enveloped by a sealed, sanitary wrapper 4. These materials must necessarily be properly sterilized before being placed in the said wrapper.

The cup 2, which is shown in detail in Fig. 3, must possess the qualities of collapsibility by folding and by rolling the same around the brush head so as to inclose the same partially, whereby the bristles of the latter will be protected and the package may be made to occupy a minimum amount of space. A well known form of collapsible cup is illustrated in the drawings, but it is to be understood that any other cup having the qualifications mentioned may be employed. The cup is impregnated with shaving soap by dipping the same in a liquid body of the latter, it being necessary merely to coat the inner surface of the cup wholly or in part with the liquid soap. This manner of affording sufficient soap for ready use in shaving is considered preferable to placing a cake or small piece of soap within the package, though the latter expedient may be resorted to in practice if found desirable. The coating of soap will be so thin and plastic as not to interfere with the folding or rolling of the cup when collapsed. If the inner surface of the cup alone is coated with soap, the outer surface of the same may be coated with paraffin or other waterproofing substance, but this is not absolutely essential, owing to the temporary nature of the use of this cup.

The brush head, which is shown in detail in Fig. 5 of the drawing, consists of a doubled bundle of bristles 5, secured medially by a wire binder 6, or the like, the base end of which bundle is fitted snugly within a band 7. The casing 1 of the package is adapted to serve eventually as a handle for the brush, and is, with this purpose in view, provided at one end with a reduced, open ended extension 8, which affords a socket in which the base band 7 of the brush head is adapted to fit, in the manner shown in Fig. 1.

In Fig. 4 of the drawing, the cup when expanded is shown mounted within a holder 9, which latter is to be provided for permanent use by each barber of any shop in which the invention is to be used. This

holder is intended to be similar to those used at soda fountains to hold the glasses in which liquid refreshments are dispensed.

The advantages of the use of a sanitary shaving outfit package of the nature described are manifold and should be readily apparent from the following description of the manner of use. When a customer enters a barber shop wherein a vending machine containing the sanitary packages is located, he drops the necessary coin into the machine and receives a package, which he knows to contain a shaving cup, brush, and soap, which have never been used for shaving purposes and are absolutely sterile. The vending machine is not illustrated, for the reason that it does not form any part of the subject matter of the present application and may be of any construction suitable for the purpose. When his turn to be shaved has arrived, he gives the package to the barber, who withdraws the wrapper 4 and its contents from the casing 1, breaks the wrapper and removes the contents. The brush head is removed from within the folded and rolled cup and is inserted within the socket 8 of the casing, as a handle. The cup is then expanded and inserted within the holder illustrated in Fig. 4. When a small quantity of warm water has been poured

into the cup, the soap coating of the latter may be worked into lather by application of the brush. After the outfit has been used, the cup and brush may be destroyed.

While the invention has been described as being intended particularly for use in barber shops, it may be used to advantage for home shaving.

Having thus described the invention what it is desired to claim and to secure by Letters-Patent, is:

A sanitary shaving outfit package comprising an open-ended casing of comparatively rigid material adapted to be used as a brush handle, a sealed sanitary wrapper fitting within the casing, and sterile shaving materials enveloped by the said wrapper and consisting of a collapsible cup, a supply of soap for the cup, and a brush head adapted to fit one end of the casing as a handle when removed from the wrapper, the cup being rolled around the brush head to economize space.

In testimony whereof I have signed my name to this specification in the presence of two subscribing witnesses.

LEOPOLD GUTMAN.
